UNITED STATES PATENT OFFICE.

WILLIAM M. MILLS, OF DAYTON, OHIO.

TURBINE WATER-WHEEL.

SPECIFICATION forming part of Letters Patent No. 293,904, dated February 19, 1884.

Application filed August 3, 1883. (No model.)

To all whom it may concern:

Be it known that I, WILLIAM M. MILLS, a citizen of the United States, residing at Dayton, in the county of Montgomery and State of Ohio, 5 have invented certain new and useful Improvements in Turbine Water-Wheels, of which the following is a full, clear, and exact description, reference being had to the accompanying drawings, making part of this specification.

10 In the said drawings, Figure 1, Sheet 1, is an elevation of my improved wheel. Fig. 2, Sheet 1, is a vertical section of the wheel on the line $x\ x$ of Fig. 3. Fig. 3, Sheet 1, is a bottom plan view of the wheel. Fig. 4, Sheet 15 2, is an elevation of the wheel-case with its contained wheel. Fig. 5, Sheet 2, is a plan view through the line $x\ x$ of Fig. 4. Fig. 8, Sheet 2, is a vertical section taken on the line $x\ x$, Fig. 5. Fig. 6, Sheet 3, is a vertical section 20 through the line $z\ z$ of Fig. 4. Fig. 7, Sheet 3, is a sectional plan view through the line $y\ y$ of Fig. 4, but with the gates in different positions of opening.

The same letters of reference are used to indicate corresponding parts in all the figures.

25 A represents the wheel-case, which, with the exceptions I will point out hereinafter, may be of the usual or any suitable construction, having the chutes B, draft-flume C, gate-ring D, 30 gate-rods E, gates F, and bridge-tree G. The chutes are formed between the bottom plate, H, and top plate, I, by vertical division-walls J, set substantially at a tangent to the periphery of the wheel, and by the gates themselves, 35 whose inner ends are pivoted at a in sockets b , formed in the walls J, as shown. That portion of each gate within the chute is slightly concave toward the wheel, as seen in Fig. 7, according to diameter of wheel. The outer 40 ends of the gates project laterally to form heads or wings c , of the shape shown, which are hollowed out to economize metal and obtain lightness combined with strength, and also to obtain a proper water-entrance. The gate-rods 45 E are connected at their inner ends to the operating-ring D, and at their outer ends are pivoted upon pins d , projecting from bridge-pieces e , between the front and rear sides of the gate-head. The ring D has an extension formed 50 into a segmental rack, f , meshing with a pinion, K, upon a vertical rod or shaft, L, which

extends up above the flume or penstock, and is provided with a hand-wheel, so that by turning said shaft L the ring D is rotated to open or close the gate simultaneously, and to any 55 extent desired. The plate I over each chute is bent upward at the mouth of the chute, as seen particularly in Fig. 8, and the gates at their outer extremities or head portion are rounded, so that I obtain a chute with two of 60 its walls flaring at the mouth, by which means the volume and force of the entering water are unbroken and a vacuum within the chute prevented. At the same time, by pivoting the gates close to the periphery of the wheel, and 65 by setting the division-walls J at the angle shown, the water is always directed effectively upon the buckets, no matter to what extent the gates may be open, as will be readily seen by reference to Fig. 7, where I have shown the 70 gates at different positions of openings, from quarter-gate to whole gate; also, by this construction I make each gate serve as one of the chute-walls. The wheel, Figs. 1, 2, 3, and 7, has an inverted conoidal hub, from which the 75 buckets project, not radially, but with their concavo-convex horizontal sections substantially tangential to the hub, no matter at what position the section may be taken, as seen in Fig. 7. Embracing the outer edges of the buckets is an 80 integral ring, M, with a flat upper projecting surface, g , which bears against and travels under the inner projecting edge of the bottom plate, H, as seen in Fig. 6. The curves of the 85 outer and inner edges of the buckets are clearly shown in Fig. 1, and it will be seen that the bucket is so shaped as to have substantially four different directions of curves—namely, a curve at top, a curve at the bottom, a curve at the outer edge, and a curve at the inner 90 edge—which have the effect of retaining the water and at the same time of directing it outward toward the periphery of the wheel, instead of to the center. It results from this construction that the space between the buckets forms a 95 throat, which is gradually contracted as it approaches the hub and as it approaches the bottom of the wheel. Perforations h , Fig. 2, are formed in the hub to permit the escape of any leakage-water, which otherwise might get over 100 the hub, and under the hydrostatic pressure would so jam the wheel as to seriously inter-

fer with its easy running. Those portions of the bottom plate, H, within the chutes are beveled off or rounded, as seen in Figs. 2 and 6, so as to present no obstruction and to lessen the friction of the entering water. The wheel is keyed to the spindle N, which is journaled and stepped into the casing in the usual or any suitable manner.

I am familiar with the construction of turbine-wheels proposed in patents of Ross, No. 152,515, of Mallory, No. 218,295, and of Crocker, No. 250,889, and do not wish to be understood as intending to cover by the following first claim anything shown or described in said 15 patents; but, in fact, I wish to be understood as disclaiming the same.

Having thus fully described my invention, I claim—

1. In a turbine water-wheel, the wheel proper, having spiral concavo-convex buckets substantially tangential to the hub, and surrounded by a projecting ring, in combination with the wheel-casing provided with chutes whose bottom walls extend over said projecting ring, and are beveled or rounded, substantially as described.

2. In a turbine water-wheel, the chutes having enlarged or flaring mouths or water-ways, formed by the turned-up upper walls thereof, and the bent or curved ends of the gates pivoted therein, substantially as described.

WILLIAM M. MILLS.
